Samuel Cline
Letters Patent.

the Vehicle referred to in these Letters Patent and making part of the same, containing a description in the words of the said Samuel Cline himself of his improvement in the Plough.

Specification or description of Samuel Cline's newly invented and improved combined Plough "being a machine for ploughing in light-free soil, for ploughing in grain, dressing Indian Corn and all other light rank of a similar kind. The principle of combination on which the due construction of this machine depends is to place the line of draft or beam so that the resistance to be overcome may bear equally on both sides of that line. To effect this the beam to which the shares are attached must be inserted five inches to the right of the middle of the hind beam, and bear to the left just so much that a perpendicular raised on the centre of said hind beam will touch the end of the main beam. The transverse beam crosses the beam of the Plough at an angle of sixty degrees. The proportion used and found convenient are about ten inches in length and eight in breadth, and the turn of the mould board should be very little beyond a perpendicular from the hinder corner of the share. The Plough consists simply of Mould-board, land-side, and sheath or standard. The mould board is drawn and flattened out at the broad edge so as to supply the place of a share. These should be made of iron and steel either hammered & rolled, or cast, at the pleasure of the maker and fastened into the transverse beam by the standard with a shoulder on the under side of the beam fitted to an iron collar and screw and nut or strong wedge on top of the beam. The standards are made fourteen inches in height, and the draft or depth of the Plough is regulated by a screw and wedge at the insertion of the main beam, and the hinder beam. The whole length of the beam being five feet two inches. The machine is found to work well with Ploughs of eight inches in breadth placed at the distance of fourteen inches from each other, thus cutting about ten inches each and using five ploughs. Two horses are able to work this combined Plough quite easily and to pass over as much land in a day as three teams of two horses each with a common single Plough. Figure No D is the principal improvement in the "combined Plough" which is calculated for two or three Ploughs only, the main beam

being inserted in a perpendicular line to the hinder beam. The moulds are formed in the same shape and of the same material as those in Figure No. 1, but with the addition of a cutter made of steel and secured to the land side and extending two or three inches beyond the mould so as to supply the place of a roller. This improvement to the machine is used for ploughing a bed down any other ground in handsome order. To construct a combined Plough. Figure No. 1. draw the line A.B. equal 2 feet. At A draw the transverse beam A.C. making the angle B.A.C. equal 60° , and the beam C.D. equal 4 feet 9 inches, direct A.B. in C. and erect a perpendicular G.C. and where this crosses the transverse beam, is the place of the centre place of the divide and beam is equal parts at the points O.O. for the insertion of the other Ploughs at 5 inches to the right of the centre of insert the beam C.D. 2 inches wide and 3 feet 2 inch is long. Let it bear to the left so that the end A.D. will touch the line G.C. At C. mount a screw and wedge for raising and depressing the beam C.D. so as to plough any required depth. To construct a "Combined Plough" Figure No. 2. draw the baseline A.B. equal $13\frac{1}{2}$ inches. B.C. equal 21. inches and the transverse beam A.G. 26 inches, making the angle B.A.G. = 60° at $5\frac{1}{2}$ inches from B insert the beam C.D. 3 feet in length, make A.a. $3\frac{1}{2}$ inches and C.c. $17\frac{1}{2}$ inches also B = 4.4 inches. At C mount the screw and wedge as in No. 1.
